[57] CLAIM

The ornamental design for a colored appointment book leaf, as shown and described.

DESCRIPTION

FIG. 1 is a front elevation view of a colored appointment book leaf showing our new design; and,

FIG. 2 is a rear elevation view thereof.

The colored appointment book leaf is flat and of conventional thickness.

The drawing is lined, in part, for the color yellow and for two different shades of blue, the darker shade of blue being lined more densely than the lighter shade of blue.

The indicia "2000" depicted by means of broken lines in the upper lefthand corner of FIG. 1 has been shown for illustrative purposes only and forms no part of the claimed design.
